C. V. HAYNES

RADIATOR VALVE

Filed Feb. 10, 1919

INVENTOR

Charles V. Haynes,

BY

W. Steel Jackson

ATTORNEY

UNITED STATES PATENT OFFICE.

CHARLES V. HAYNES, OF PHILADELPHIA, PENNSYLVANIA, ASSIGNOR TO HOFFMAN SPECIALTY COMPANY, OF NEW YORK, N. Y., A CORPORATION OF ILLINOIS.

RADIATOR VALVE.

Application filed February 10, 1919. Serial No. 276,156.

To all whom it may concern:

Be it known that I, CHARLES V. HAYNES, a citizen of the United States, residing at Philadelphia, in the county of Philadelphia and State of Pennsylvania, have invented a certain new and useful Radiator Valve, of which the following is a specification.

My invention relates to valves of the character shown in my Patents Nos. 1,277,413, of September 3, 1918, and 1,283,752 of November 5, 1918, intended for use with all types of hot water, vapor, vacuum, modulating or atmospheric heating systems.

The main purpose of my invention is to make the parts more accessible for withdrawal for repairs while retaining all the advantages of the valves of the patents.

A further purpose is to utilize the outer shell of the valve to perform the function of the fixed shells of these two patents, reducing the size and weight of the valve and giving a more direct fluid path between the inlet and outlet openings.

Further purposes will appear in the specification and in the claims.

I have preferred to illustrate my invention by but one form thereof, selecting a form which is practical, highly efficient and having the advantages of my said patent forms though much cheaper to manufacture than either, and which at the same time well illustrates the principles of my invention.

Figure 1 is a central longitudinal section through the valve.

Figure 2 is a central longitudinal section through the casing, the parts being removed, taken at right angles to the section in Figure 1.

Figure 3 is a top plan view of the structure seen in Figure 1.

Figure 4 is a side elevation of one of the parts.

Figures 5 and 6 are sections upon line 5--5 in Figure 1, the parts being in different relative positions.

In the drawings similar numerals indicate like parts.

The outer shell of the valve is shown at 10. It is provided with a threaded inlet opening at 11 and with an outlet at 12 which is connected with threaded outlet pipe 13 by means of a coupling 14.

Whereas, the inlet in each of my patents

is made through a removable bottom closure, in my present valve I form the bottom solid except for the inlet indicated.

The outer casing is bored at 15 to provide a barrel taking the place of the sleeves (such as 12 in Patent No. 1,283,752) in my patents, above stated, and this boring operation is extended below the opening 16 from the barrel into the outlet to provide an annular depression, as shown at 17 about a raised seat 18 surrounding the inlet opening.

The opening 16 is rectangular in cross section in order that its communication with the barrel may correspond with the rectangular slotting or openings within the cylinders or shells of my patents. The barrel with its lower raised seat and the rectangular outlet connection corresponds generally with the inserted sleeve 12 as seen in my Patent 1,283,752, having an enclosed seat and rectangular slotted outlet opening through the sleeve.

The construction described greatly reduces the required diameter of the valve casing and provides much more direct communication of the fluid from the inlet to the outlet, while at the same time giving a conformation to the parts corresponding to that which was obtained by the larger, heavier and more expensive construction of Patent No. 1,283,752, for example.

As the barrel construction described requires no parts removable from the lower end for machining, all of the separable parts can be made removable readily from the top of the valve and are so constructed. This makes the parts much more easily accessible for repairs or replacement.

My present valve is capable of using the same character of valve parts as are used in my patents and I have shown the parts as corresponding closely with those in Patent No. 1,283,752.

The valve 19 is intended to move vertically, but not to rotate, within a shell 20, provided with an opening 21. The shell is retained in a cap 22 and is sealed against leakage between it and the cap by packing 23. Nut 24 holds the parts in position above an indicating disk 25. As in my previous constructions the shell may be adjusted in different angular positions so as to have the opening 21 correspond wholly or partly, as

desired, with the rectangular opening 16, the position in which it is set being shown by the indicating disk. The different positions are shown in Figures 5 and 6.

5 The valve 19 is provided with a filler member 26 for the opening 21, and is itself carried by a screw 27, hollow and of rectangular interior section, which turns in a thread within the shell. It is turned by a 10 square head 28 upon a spindle 29. These parts are upwardly pressed by a spring 30 and the upward thrust is taken by a nut 31 through handle 32. A collar 33 upon the spindle engages the packing 34 to seal 15 against leakage past the spindle.

The cap 22 is removable from the body of the valve and is held in place thereon by a threaded flange 35 which compresses packing 23 against the top of the valve to seal 20 at this point.

In operation:—the shell 20 is set to the position for full opening or such proportion thereof as may be desired when the valve is raised. The handle is then turned to close 25 or open the valve. The filler piece 26 performs the same function in sealing from fluid flow the upper part of the opening 21 which is out of line with the outlet opening 16, as in my patents named.

20 The simplification of the parts, their removability from above for repairs or replacements, and the savings in weight and cost will be recognized in this art as de-

cided advantages eagerly sought by all interested in radiator valves. 35

Having thus described my invention, what I claim as new and desire to secure by Letters Patent is:

1. In a radiator valve, a body having an inlet at the bottom, a valve seat coaxial with the inlet and an outlet of rectangular section at the side, an adjustably held sleeve fitting in the body and having an opening corresponding in shape with the outlet section, a cap and connections retaining the sleeve in position and holding the end of the sleeve against the body about the valve seat, packing sealing the cap against the body and sleeve and the joint between them, a valve carried by the sleeve and adapted to engage the valve seat and rotary axially-fixed means for rotating the valve. 40 45

2. In a radiator valve, a body having an inlet at the bottom, a valve seat coaxial with the inlet and an outlet of rectangular section at the side, a sleeve fitting in the body and having a flange registering substantially with the upper edge of the body, packing engaging the flange and edge of the body, a cap holding the packing in position 50 and forcing the sleeve against the body about the valve seat, the valve carried by the sleeve and adapted to engage the seat and operating mechanism for said valve. 55 60

CHARLES V. HAYNES.
